UNITED STATES PATENT OFFICE.

JULIAN S. GRAVELY, OF WYTHEVILLE, VIRGINIA, ASSIGNOR TO WINCHESTER REPEATING ARMS COMPANY, OF NEW HAVEN, CONNECTICUT, A CORPORATION OF CONNECTICUT.

FOCUSING HANDLAMP.

Application filed January 7, 1924. Serial No. 684,700.

To all whom it may concern:

Be it known that I, JULIAN S. GRAVELY, a citizen of the United States, residing at Wytheville, in the county of Wythe, State of Virginia, have invented certain new and useful Improvements in Focusing Handlamps; and I do hereby declare the following to be a full, clear, and exact description of the invention, such as will enable others skilled in the art to which it appertains to make and use the same.

This invention relates to battery hand lamps of the type disclosed in the patent granted to A. L. Staples, February 13, 1923, No. 1,445,245, wherein the character of the beam of light can be altered by varying the position of the lamp bulb with respect to the reflector.

The principal object of this invention is to provide a lamp support of simple construction, the principal feature being the provision of a metal lamp socket which can be moved with respect to a reflector supported out of contact with the lamp socket. In order to make a hand lamp of this character, it has heretofore been considered necessary to provide a special lamp socket constructed in such a manner that the lamp bulb is insulated from the reflector which is in contact with the lamp socket, and such that the necessary electric connections for the lamp bulb are provided in the lamp socket. It has therefore been considered necessary, as shown by the Staples patent above referred to, to provide a lamp socket consisting of insulating material, this socket being constructed in such a manner that electric conductors can be brought into contact with the central conductor of the lamp bulb and with the outer conductor of the bulb.

The present invention provides improved means for supporting the lamp reflector out of contact with the lamp socket. A metal lamp socket is used and a support for this socket is provided together with means whereby this support can be moved so as to alter the position of the lamp socket with respect to the reflector. A conductor is provided in contact with the lamp socket and insulated from the socket support, for connecting one of the lamp terminals to the ordinary contact strip of the hand lamp. Means are provided for insulating this con-

ductor from the lamp socket support; and a central rivet is provided for fixing the several parts together, this rivet also serving as a means for connecting the central terminal of the lamp bulb with the carbon electrode of the battery. An additional feature of this invention comprises means for preventing the lamp socket and the conductor associated therewith from turning with respect to the lamp socket support when a lamp bulb is screwed into the socket, even though the central rivet which is supposed to fix the several parts together is loose.

Further objects of the invention are to group the several elements compactly so that a casing of minimum length can be used, to provide for economical manufacture and assembly of the several parts, to provide for ready access to the various parts of the hand lamp mechanism, in case repairs are necessary, and to insure against short circuiting of the battery and inadvertent lighting of the lamp. The various objects and advantages of this invention will be apparent upon considering the following detailed description which is to be considered in conjunction with the accompanying drawings, in which,

Fig. 1 is a sectional elevation of one embodiment of my invention.

Fig. 2 is a fragmentary section of a different embodiment showing the application of the invention to a hand lamp having a metal casing instead of a casing of insulating material, such as that shown in Fig. 1.

Fig. 3 is a transverse section taken on line 3—3 of Fig. 1 showing the details of construction.

Fig. 4 is a detailed view in section showing several parts of the improved hand lamp mechanism and illustrating the manner in which these parts are assembled.

Fig. 5 is an elevation of the improved lamp socket support.

Fig. 6 is an elevation of the improved conductor used for the purpose of connecting the lamp socket to the conducting strip of the hand lamp.

Fig. 7 is an elevation of an insulating washer used for the purpose of insulating the conductor shown in Fig. 6 from the lamp socket support.

Fig. 8 is an end elevation of the improved

lamp socket showing the details of the construction.

In the embodiment illustrated in Figs. 1 and 3 to 8 incl. of the accompanying drawings, the hand lamp comprises a casing 1, of insulating material, such as fiber, in which are located a plurality of dry cells placed end to end in a pasteboard carton 2, in conformity with usual practice. The bottom of 10 the lowermost dry cell rests on and makes electrical connection with a coil spring 3, carried by a metal bottom cap 4, threaded to a collar 5 on the casing 1. A metal strip 6 connects the collar 5 with the usual switch 15 housing 7.

The switch mechanism comprises a thumb actuated push button 31 at one end of a yielding conductor fastened to and in electrical connection with the housing 7 by 20 rivet 32. By pressing inward on the push button 31 electrical connection can be established between the bottom electrode of the battery and the outer terminal of the lamp, for in this manner the push button is brought 25 into direct contact with the rear end of the contact strip 17. A sliding thumb piece 33 carries a finger 34 which, on inward pressure of the push button 31, will disengage from a slot in the yielding member supporting 30 this button, and can be pushed forward to hold the switch in position for lighting the lamp continuously.

At the opposite or front end of the casing 1, and forming a part thereof, is a flaring 35 metal head 8 fastened to the fiber tube by rivets 9, and having its front portion threaded to receive a lens retaining ring 10. A reflector 11, substantially parabolic in outline, has its outer edge gripped between the lens 12 and a support 13, formed by the converging front end of the flaring metal head 8. The lens 12 may be plain, as shown, or it may be curved. A reinforcing ring 14 is provided between the annular support 13 45 for the reflector, and the retaining ring 10. This reinforcing ring may be in the form of a piece of wire bent to form a loop, and inserted in a suitable annular recess formed in the retaining ring 10. This reinforcing ring, 50 when arranged in this manner, is permanently associated with the retaining ring so that when the retaining ring is unscrewed the reinforcing ring remains in position in its annular groove or seat. The reflector 11 55 is firmly held against the support 13 by the retaining ring 10, which clamps the lens 12 against the rim of the reflector and forces this rim into firm contact with the annular support 13. The ring 14 forms a substantial 60 support or reinforcing means for the outer end 13 of the flaring metal head.

The incandescent lamp bulb 15 is threaded into a metal lamp socket 16 which is electrically connected to the usual conducting 65 strip 17 of the hand lamp by means of a

conductor 18, which is in direct contact with the lamp socket. A metal rivet 19 passes through the bottom of the lamp socket and serves as a means for making electrical connection between the inner lamp terminal and 70 the upper electrode 20 of the battery.

The lamp socket 16 is carried by a three-legged support or spider 21, the three legs of which project through the casing 1 of the hand lamp. In fact, these legs project 75 through longitudinal slots formed in the hand lamp casing in such a manner that the support 21 can be moved longitudinally of the hand lamp casing. The head 8 of the hand lamp is provided with screw threads 80 22 at the inner end thereof, and a threaded ring 23 having an annular passage therein, is adapted to be screwed onto this threaded portion 22 of the head of the hand lamp casing. The projecting legs of the lamp socket 85 support extend into the annular passage within the ring 23, so that when this ring is turned the support 21 is caused to move forward or backward, depending upon the direction of rotation of the ring 23 with respect to the hand lamp casing. The ends of the legs of the support 21 are offset as shown in Fig. 1 at 30, so that the body portion of this support is disposed nearer the battery than the portions which engage the adjusting ring 23.

An insulating washer 24 is provided in the base of the metal lamp socket 16 for the purpose of insulating the socket from the central rivet 19. The conductor 18 encircles the rivet 19 but is insulated therefrom by a small insulating washer 25. The support 21 is provided with a central opening into which is fitted a piece of insulating material 26. This piece of insulating material is in 105 the form of a washer encircling the rivet 19. An insulating washer 27 is provided for the purpose of insulating the conductor 18 from the support 21. This conductor 18 is thus not only insulated from the rivet 19 but also 110 from the support 21. A metal washer 28 is provided just below the inner head of the rivet 19 and an insulating washer 29 separates the metal washer 28 from the support 21.

The several parts described in the preceding paragraph can be assembled in the manner illustrated in Fig. 4. The insulating washer 24 can be inserted in the lamp socket until it rests on the bottom thereof, and then the parts numbered 25, 18, 27, 21, 26, 29 and 28 can be applied to the bottom of the lamp socket in the order named. The rivet 19 is then inserted from the inside of the lamp socket, and the projecting end of this rivet 125 spun over, as shown in Fig. 1, to clamp the several parts together.

A satisfactory hand lamp embodying this invention can be constructed in accordance with the above description, but I prefer to 130

employ certain additional features which add to the value of this device. For example, I prefer to provide means for preventing the insulating washer 26 from rotating with respect to the support 21, when a bulb is screwed into the socket 16. In order to accomplish this result, the opening provided in the support 21 can be made irregular. The general shape of this opening may 10 be irregular, or the edge of the opening may be corrugated as shown in Fig. 5.

I also prefer to provide means for preventing the lamp socket and also the conductor 18 from rotating with respect to the insulating washer 26 and the support 21, when a lamp bulb is screwed into the socket. A simple and effective means for accomplishing this result consists of a lug 35, struck from the base of the metal lamp socket 16 20 and adapted to enter a depression indicated at 36 in the washer 26. The conductor 18 is provided with a keyway shown at 37 in Fig. 6, which also receives the lug 35. In this manner both the lamp socket and the conductor 18 are permanently locked to the washer 26 which is, in turn, fixed to the support 21 by virtue of the corrugations thereon. It is thus impossible for the socket 16 25 or any of the parts associated therewith to rotate when a lamp bulb is screwed into the socket, even though the central rivet 19 is loose.

In Fig. 2 I have illustrated a hand lamp having a metal casing 1'. The present invention can be used with a hand lamp of this type exactly as well as with a hand lamp having a casing consisting of insulating material. Where a metal casing is used, it is merely necessary to insulate the conducting strip 17 from the casing. This can be done by providing a sheath 38 of insulating material. The sheath and the conducting strip can be fixed to the metal casing by means of metal rivets 39, which pass through 40 both the sheath and the conducting strip. When this construction is employed, the holes in the conducting strip should be substantially larger than those in the insulating sheath, so that when the rivets are fixed in place the insulating sheath will separate the rivets and the conducting strip in the manner shown in Fig. 2. The other parts of the switch mechanism of Fig. 2 are exactly the same as those illustrated in Fig. 1, and the same reference characters are applied to like parts in these two figures.

It will be noted from the above description that this invention includes a hand lamp having a metal socket which can be adjusted 50 with respect to the reflector to change the character of the beam of light. This metal socket which is of simple construction is supported in a convenient manner by parts that can be easily manufactured and readily assembled. An important feature of the in-

vention consists of the construction of the means for supporting the reflector, whereby this reflector is supported out of contact with the lamp socket. Since there is no actual contact between these parts, it is not necessary to provide either a socket made of insulating material, or insulation arranged between a metal socket and the reflector. 70

While I have described certain specific means for accomplishing certain purposes relating to hand lamp mechanisms, it is to be understood that other means may be employed without departing from the principle of the invention. Various changes in the details of construction can be made and so various parts can be omitted without departing from the scope of the invention as defined in the appended claims. 75

I claim:

1. In a hand lamp, the combination of a metal lamp socket, a reflector, means for supporting said reflector at its outer edge and means for supporting the lamp socket having portions extending through the hand lamp casing whereby the position of said socket with respect to said reflector can be changed, the said reflector being entirely out of contact with the lamp socket and the lamp socket support. 85

2. In a hand lamp, the combination of a metal lamp socket, a reflector, means for supporting said reflector at its outer edge, a metal spider support for said lamp socket, means for insulating said socket from said socket support and means whereby the position of said socket with respect to said reflector can be changed, the said reflector being entirely out of contact with the lamp socket and the lamp socket support. 95

3. In a hand lamp, the combination of a metal lamp socket, a reflector, a support for said socket, means for insulating said socket from said support, means carried by said socket for preventing said socket from rotating with respect to said support, and means for extending thru the hand lamp casing for moving said support to change the position of said socket with respect to said reflector. 105

4. In a hand lamp, the combination of a metal lamp socket, a reflector, a support for said socket, means for insulating said socket from said support, means carried by said socket for preventing said socket from rotating with respect to said support, means for extending thru the hand lamp casing for moving said support to change the position of said socket with respect to said reflector, and means for supporting said reflector out of contact with said socket. 115

5. In a hand lamp, the combination of a metal lamp socket, a reflector, a support for said socket, means for insulating said socket from said support, a conductor in contact with said socket, means for insulating said conductor from said support, and 125

- means extending thru the hand lamp casting for moving said support to change the position of said socket with respect to said reflector.
5. In a hand lamp, the combination of a metal lamp socket, a reflector, a metal spider support for said socket, means for insulating said socket from said support, a conductor in contact with said socket, means 10 for insulating said conductor from said support, means for moving said support to change the position of said socket with respect to said reflector, and means for preventing said socket and said conductor from 15 rotating with respect to said support.
7. In a hand lamp, the combination of a metal lamp socket, a reflector, a support for said socket, a piece of insulating material interposed between said socket and said 20 support, means for preventing said socket from rotating with respect to said insulation, separate means for preventing said piece of insulation from rotating with respect to said support, and means for moving said support to change the position of 25 said socket with respect to said reflector.
8. In a hand lamp, the combination of a metal lamp socket having a lug projecting from the base thereof, a support for said 30 socket having a central opening, a piece of insulation fixed in said opening and having a depression adapted to receive the lug on said socket, a conductor in contact with said socket, and having a keyway adapted to receive the lug on said socket, insulation interposed between said conductor and said support, and means for fixing the several 35 parts together.
9. In a hand lamp, the combination of a metal lamp socket, a support having a central opening, an insulating washer in the base of said socket, an insulating washer fixed in the opening in said support, a conductor in contact with said socket, means for insulating said conductor from said support, and a rivet for fixing the several parts together, the said rivet being insulated from 40 said conductor and said support.
10. In a hand lamp, the combination of a metal lamp socket, a support having a central opening with a corrugated edge, an insulating washer fixed in the opening in said support, a conductor in contact with said socket, means for insulating said conductor from said support, a rivet for fixing the several parts together, the said rivet being insulated from 45 said conductor and said support.
11. In a hand lamp, the combination of a reflector, a lens, a retaining ring for clamping said lens against said reflector, a support for said reflector, and a reinforcing ring disposed between the edge of said support and the retaining ring.
12. In a hand lamp, the combination of a reflector, a lens, a retaining ring for clamping said lens against said reflector, a support for said reflector, and a reinforcing ring carried by said retaining ring and adapted to reinforce the edge of said support.

In testimony whereof I affix my signature.
JULIAN S. GRAVELY.
